CLAIM

The ornamental design for a doorknob, as shown and described.

DESCRIPTION

FIG. 1 is a top, front, right side perspective view of a doorknob;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a rear view thereof.

All broken lines illustrate portions of the doorknob that form no part of the claimed design.
